ARTICLE POLISHING OR GRINDING MACHINE.

1,267,574.

Specification of Letters Patent.

Patented May 28, 1918.

Application filed May 7, 1917. Serial No. 167,072.

To all whom it may concern:

Be it known that I, FRANK H. MOONEY, a citizen of the United States, and a resident of Toledo, in the county of Lucas and State of Ohio, have invented a certain new and useful Article Polishing or Grinding Machine; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to grinding, polishing and buffing machines, and particularly to a machine adapted for the polishing or buffing of small articles, such for instance, as fountain pen caps, barrels, etc.

The object of my invention is the provision of a simple and improved machine of the character described, which is automatically operable to successively take work pieces from a magazine, polish and then deliver them from the machine, whereby the polishing of articles of the character described is accomplished in an efficient and rapid manner.

The invention is fully described in the following specification, and while, in its broader aspect, it is capable of embodiment in numerous forms, a preferred embodiment thereof is illustrated in the accompanying drawings, in which—

Figure 1 is a top plan view of a machine embodying my invention. Fig. 2 is a side elevation of the abrasive applying means for one of the buffing wheels. Fig. 3 is a side elevation of a portion of said means. Fig. 4 is a section on the line 4—4 in Fig. 1. Fig. 5 is a section on the line 5—5 in Fig. 1. Fig. 6 is a bottom plan view of a portion of the frame base or table together with the mechanism mounted thereunder. Fig. 7 is a section on the line 7—7 in Fig. 1, and Fig. 8 is an enlarged detail of a portion of the pawl and ratchet means shown in Fig. 6.

Referring to the drawings, 1 designates a table or frame base, on the top of which are mounted two standards 2 and 3, in the present instance, in diagonally spaced relation with respect to the table. The upper ends 55 of the standards 2, 3 form bearing heads in

which horizontal shafts 4 and 5 are respectively mounted. Buffing or polishing wheels 6 and 7 are mounted on the inner ends of the respective shafts 4, 5 to turn therewith, while the outer ends of said shafts have pulleys 8 and 9 mounted thereon, respectively, and belted or otherwise connected to a suitable source of power. The peripheries of the wheels 6 and 7, in the present instance, are concaved in cross-section. It will be understood, however, that the character of said wheels and the shape of the peripheries thereof may be changed to suit the conditions of use. If the machine is to be used for grinding instead of polishing or buffing purposes the wheels 6 and 7 may be made of carborundum or other materials suitable for the purpose. The wheel 6, in the present instance, is employed as the rough polishing wheel 75 and the wheel 7 is employed to impart the finishing polish to the articles acted on.

The table 1 is provided between the standards 2 and 3 with a vertical bearing 10 in which a vertical shaft 11 is mounted for 80 rotary and yielding axial movements. The lower end of this shaft projects below the table and carries a ratchet-wheel 12 and the upper end of the shaft projects above the standard and carries a rotary head or disk 85 13, from which a plurality of work carrying arms 14 (in the present instance, four in number) radially project in equidistantly spaced relation. A coiled compression spring 15 encircles the shaft 11 between the 90 upper end of the bearing 10 and a collar 16 fixed to the shaft and serves to yieldingly support the shaft in normal position with respect to the bearing. The shaft 11 is intended to have quarter turning movements 95 intermittently imparted thereto and for this purpose a bearing arm 17 projects from the under side of the table 1 below the ratchet-wheel 12 and carries a shaft 18 in axial register with the lower end of the shaft 11. 100 Two crank-arms 19 and 20 are carried by opposite ends of the shaft 18, the arm 20 being disposed adjacent to the under side of the wheel 12 and carrying a pawl 21 in position to successively engage within each of 105 a set of four recesses 22 provided in equidistantly spaced relation in the lower peripheral edge portion of the wheel 12. A spring finger 23 is fixed to the arm 20 and acts on the pawl 21 to cause it to yieldingly 110

bear against the registering edge portion of the ratchet-wheel.

The arm 19 is connected by a bar 24 to a crank-arm 25, which is fixed to the lower end of a vertical shaft 26, that projects upward through the table 1, being mounted in a suitable bearing 27 provided therefor. In order that the arm 19 may have only a quarter revolution imparted thereto at each revolution of the crank-arm 25, the bar 24 is provided with a longitudinally extending slot 28 for receiving the connecting pin or bolt 29 on the arm 19, thereby enabling the arm 19 to remain stationary during portions of the reciprocatory movements of said bar, as is apparent. The shaft 26 carries a worm-wheel 30 in mesh with a drive-worm 31 on a shaft 32, which shaft is mounted in horizontal position in suitable bearings at the under side of the table. A pulley 33 is carried by the shaft 32 and projects partially through an opening 34 provided therefor in the table 1. This pulley may be belted to any suitable source of power.

A pair of parallel arms 35, 35 fixedly rise from the table 1 adjacent to the shaft 26 and coöperate to form a vertical guide or slide-way for a slide 36. A plate 37 connects and is secured to the front side of the guide bars 35, closing the space therebetween for a portion of the length of said bars and a work holding box or magazine 38 is fixed to and projects from the opposite side of said guide bars. The bottom of the magazine 38 inclines outward from the bars 35 so that work pieces A in said magazine will feed by gravity toward and into the space between the bars 35, being prevented by the plate 37 from passing entirely through the space between the bars. When the slide 36 is lowered its upper end is disposed adjacent to the lower edge of the magazine 38 so that upon each raising movement of the slide a work piece will be carried upward thereby between the guide bars 35 and deposited over the top edge of the plate 37 into a trough 39 provided therefor, said trough, in the present instance, being integral with the top edge of the plate 37 and horizontally disposed. The upper end of the slide 36 is dished, as shown at 36^a, to facilitate a raising of a work piece thereby, said dished portion being inclined toward the plate 37 so that the work piece automatically passes down over the top of the plate and into the trough 39 when raised a sufficient height for such purpose. The trough 39 is radially disposed with respect to the turn-table 13 and is in position for one of the arms 14 on said table to longitudinally register therewith each time the table is at rest, thereby enabling a work piece A, which is of tubular form, such for instance as a fountain pen cap or barrel, to be moved longitudinally 65 from the trough 39 and onto the registering

end of an arm 14 with the arm end loosely entering the same, so that the work piece is carried by the arm during a portion of its revolution and until subsequently released after being polished, as hereinafter described.

An arm 40 pivotally projects from a side of the bearing 10 for vertical swinging movements and is connected at its outer end by a link 41 to the lower end of the slide 36, whereby rocking movements of said arm impart reciprocatory movements to the slide. A bell-crank lever 42 is fulcrumed to a bracket 43 on the table 1 in advance of the guide-bars 35 and has its horizontally projecting arm connected by a link 44 to the rocker-arm 40 and its vertically disposed arm extending above the trough 39 and extending over and downward therein for movements lengthwise within the trough 85 when the lever is rocked. A spring 45 normally retains the lever 42 in position for its upper hooked end to stand at the outer end of the trough 39 so that a movement of the lever from normal position will cause its 90 hooked end to engage the outer end of a work piece disposed in the trough and force said work piece forward onto a registering turn-table arm 14. The shaft 26 is disposed adjacent to the lever 42 and carries a cam-wheel 46 at its upper end in peripheral engagement with a lug 47 on the vertically disposed arm of the lever 42, whereby a turning of said cam-wheel will impart a work feeding stroke to the lever 42 at each operating stroke of the pawl 21.

An abrasive or polishing material applying means is associated with each polishing or buffing wheel 6, 7 and comprises a rocker-arm 48, which pivotally rises from a bracket 49 on the table 1 at the outer side of the respective polishing wheel, and this arm is provided at its upper end with a head 50, in which a holder 51 for a cake of abrasive material 52 is mounted for reciprocatory 110 movements in radial relation to the associated wheel. The rocker-arm 48 has swinging movements toward and away from the periphery of the wheel to place the outer end of the abrasive cake 52 into and out of 115 contact with the wheel periphery. The outward movements of the arm 48 with respect to the wheel are limited, in the present instance, by a strap 53, which connects a laterally projecting pin 54 on said arm to the 120 bearing 10. The means for imparting inward movements to the rocker-arm 48 will be hereinafter described.

A shaft 55 is rotatably mounted in one side of the head 50 and carries a ratchet-wheel 56 at its outer end and has its inner end portion threaded through an arm 57 projecting laterally from the forward end portion of the holder 51, whereby turning movements of the shaft 55 impart longi- 130

tudinal adjusting movements to said holder. A rocker-arm 58 is pivoted at its lower end to a side of the head 50, as at 59, and has its upper end connected to one end of a draft-bar 60, which projects horizontally from the rocker-arm 58 across one side of the turn-table 13 and has a notch 61 in an edge thereof in position to be engaged by each of a plurality of pins 62 on the top of the turn-table at each revolution thereof. The pins 62 correspond in number to the arms 14 on the turn-table and engage the bar-notch 61 in a direction to impart an inward longitudinal movement to such bar and an inward rocking movement to the arm 58, the engaged pin automatically disengaging the notch in the bar at a pre-determined point in a revolution of the pin, as is apparent by reference to Fig. 1.

20 The other abrasive material carrying means, or that associated with the wheel 7, is the same in construction as that above described and has its draft-bar 60^a notched, as at 61^a, and engaging the respective pins 62 at the opposite side of the turn-table axis to the point of engagement of said pins with the bar 60. The diametrically opposed pins 62 are intended to engage the notches in the respective draft-bars at the same time 25 and to impart simultaneous movements in opposite directions to said bars as the turn-table is intermittently rotated. A coiled contractile spring 63 connects the two draft-bars in a manner as shown to resist the inward arm rocking movements thereof and to return them to normal positions after the draft-bars have been released by the respective pins 62.

65

vancing of the holder 51 and abrasive cake 52 to compensate for the wear on the abrasive cake by reason of the contact of the abrading wheel therewith. A spring finger 67 is secured at one end to a side of the rocker-arm head 50 and extends at its other end over the cake 52 and yieldingly bears thereagainst to retain it in the holder 51 and also to retain the holder in sliding engagement with the head 50.

70 When each arm 14 has turned past the finishing abrading wheel 7 the work piece A thereon moves over a work delivery wheel 68, which is so located and turns in such a direction with respect to the turn-table as to force the coacting work piece from the arm 14 and into the mouthpiece 69 of a delivery chute 70 by means of which the work piece is directed to any suitable point of discharge. The wheel 68 is carried by a shaft 71, that is mounted in a bearing bracket 72, rising, in the present instance, from the base portion of the bearing standard 3. The shaft 71 also carries a pulley 73, that is belted to any suitable 80 source of power.

85 In the operation of my machine, work pieces A are successively delivered to the trough 39 from the magazine 38 by the slide 36 and are delivered in the same order from 90 said trough to the arms 14 as they successively move into longitudinal register therewith, such delivery of the work pieces to the arms being effected by the work feeding arm 42. Each intermittent partial turning movement of the turn-table 13 places one arm 14 in work receiving register with the trough 39 and two diametrically opposed arms 14, each of which carries a work piece, in position for the work pieces thereon to have polishing engagement one with the initial polishing wheel 6 and the other with the final polishing wheel 7. As the successive arms 14 pass by the delivery wheel 68, during each intermittent movement of the wheel, the 100 work piece on such arm is frictionally engaged by the periphery of said wheel and forced outward from engagement with the arm and into the receiving mouth of the delivery chute 70. Each intermittent rotary 105 movement of the turn-table 13 also moves the respective draft-bars 60 and 60^a to place the cakes of abrasive material 52 into and out of engagement with the peripheries of the respective wheels 6, 7 and at the same 110 time the screw-shifts 55 are turned to impart a slight inward adjusting movement to the cake-holders 51.

115 It is evident that I have provided a simple and efficient mechanism for automatically 120 feeding work pieces in successive order to different arms or carrying parts of a revolving member, that these work pieces are successively acted on by different abrading members to impart initial and final polishing 125 130

operations thereto and that a work piece after being finally polished is delivered from the carrying member to any suitable point, thus providing a machine for rapidly and 5 economically polishing cylindrical objects, such for instance as fountain pen caps or barrels, without necessitating an operator handling each article for such purpose.

I wish it understood that my invention is 10 not limited to any specific construction, arrangement or form of the parts, as it is capable of numerous modifications without departing from the spirit of the claims.

Having thus described my invention, what 15 I claim as new, and desire to secure by Letters Patent, is—

1. In a machine of the class described, rotatable means having a plurality of work carrying arms projecting therefrom, means 20 for feeding cylindrical work pieces into rotatable carrying position on each arm at a predetermined point in a revolution thereof, means for rotating the work pieces on the arms and polishing the same at a predetermined point in a revolution thereof, and means for delivering a polished work piece from each arm at a predetermined point in a revolution thereof.

2. In a machine of the class described, a 30 revolute arm, means operable to impart intermittent revolute movements thereto, means automatically operable to deliver a work piece to carrying position on said arm at a predetermined point in a revolution thereof, the work piece being rotated on the arm when carried thereby, and means operable to act on the work piece at a predetermined point in a movement of said arm to both rotate the work piece on the arm and to 40 abrade the same.

3. In a machine of the class described, a revolute arm, means operable to impart step by step revolute movements to said arm, means automatically operable to deliver 45 a work piece to carrying position on said arm at a predetermined point in its movement, the work piece being carried by the arm for rotary movements thereon, and separate means both operable on the carried work 50 piece at different points in a revolution of the arm to rotate the work piece on the arm and to abrade the same.

4. In a machine of the class described, rotatable means having a projecting arm 55 means for imparting intermittent rotary movements to said first means, means for feeding a work piece onto said arm for rotary movements thereon when the arm is at a predetermined point in a revolution thereof, and means for acting on each work 60 piece at a predetermined point in its revolution with its carrying arm to rotate the work piece on the arm and to abrade the same.

5. In a machine of the class described, 65 rotatable means having a plurality of pro-

jecting arms, means for imparting intermittent rotary movements to said first means, means for feeding a work piece onto each arm for rotary movements thereon at a predetermined point in a revolution of the arm, 70 and separate means for successively acting on each work piece at different predetermined points in a revolution of the arm carrying the same to rotate the work piece on the arm and to abrade the work piece. 75

6. In a machine of the class described, a work holding magazine, a revolute arm, and mechanism operable to periodically move said arm into work receiving relation to said magazine and to feed a hollow work piece from said magazine onto said arm when in work receiving position for rotary movements thereon.

7. In a machine of the class described, revolute work carrying means, a work holding magazine at one side of said means, and mechanism operable to intermittently rotate said means and to feed a work piece from the magazine into carrying position on said means at each period of rest of said means, 90 said mechanism having an oscillating work feed arm.

8. In a machine of the class described, revolute work carrying means, a work holding magazine having a trough part, a member operable to successively deliver work pieces to said trough from said magazine, a second member operable to move work pieces from said trough into work carrying 95 position on said means, and mechanism operable to impart intermittent rotary movements to said first means and to periodically operate each of said members. 100

9. In a machine of the class described, a work carrying magazine, means revolute 105 with respect to said magazine and having a plurality of work carrying arms, mechanism automatically operable to intermittently move said revolute means to successively move the arms thereof into work receiving 110 relation to said magazine and to feed a work piece from the magazine into carrying position on each arm when in work receiving position, and means for acting on work pieces carried by said first means to 115 abrade the same.

10. In a machine of the class described, revolute work carrying means, a work holding magazine at one side of said means, mechanism operable to intermittently rotate 120 said means and to feed a work piece from the magazine into carrying position on said means at each period of rest of said means, and means for acting on work pieces carried by said first means to abrade the same. 125

11. In a machine of the class described, revolute work carrying means, a work holding magazine having a trough part, a member operable to successively deliver work pieces to said trough from said magazine, a 130

- second member operable to move work pieces from said trough into work carrying position on said rotatable means, mechanism operable to impart intermittent rotary movements to said first means and to periodically operate each of said means, and means for acting on work pieces carried by said first means to abrade the same.
12. In a machine of the class described, a revolute arm, means operable to impart intermittent revolute movements to said arm, means automatically operable to feed a work piece in carrying position on said arm at a predetermined point in a revolution thereof, a set of abrading wheels for successively acting on a work piece carried by said arm at different points in a revolution thereof, and means associated with each abrading wheel and periodically operable to apply an abrading material thereto.
13. In a machine of the class described, a turn-table having a plurality of work carrying arms projecting therefrom and having a plurality of pins projecting from one side thereof, an abrading wheel for acting on a work piece carried by each arm at a predetermined point in a revolution of the arm, and means periodically operable by the pins on said turn-table to apply an abrading material to said wheel.
14. In a machine of the class described, a turn-table having a plurality of work carrying arms projecting therefrom and having a plurality of pins projecting from one side thereof, an abrading wheel for acting on a work piece carried by each arm at a predetermined point in a revolution of the arm, and means periodically operable by the pins on said turn-table to apply an abrading material to said wheel, and to periodically adjust said material with respect to the wheel.
15. In a machine of the class described, work carrying means, a work holding magazine having a trough part, a member operable to deliver work pieces to said trough from said magazine, a second member operable to move work pieces from said trough into work carrying position on said means, and mechanism operable to periodically operate each of said members.
16. In a machine of the class described, work carrying means, a work holding magazine having a trough part, a slide operable to deliver work pieces to said trough from said magazine, an oscillating arm operable to move work pieces from said trough into work carrying position on said means, and mechanism connected to both said slide and arm and operable to periodically operate the same.
17. In a machine of the class described, a rotatable member having a revolute work carrying part, an abrading wheel for acting on a work piece carried by said member at a predetermined point in a revolution thereof, an abrading material carrying means movable into and out of operative relation to said wheel, a link projecting from said means to said member and normally standing in one position, said link and member having parts which periodically interengage during a rotation of the member to impart longitudinal movement to said link from normal position and to impart predetermined movements to said means.
18. In a machine of the class described, a rotatable work carrying table having a pin projecting therefrom for revolute movements therewith, an abrading-wheel for acting on a work piece carried by said table at a predetermined point in a revolution thereof, abrading material carrying means mounted for oscillatory movements relative to said wheel, a link extending from said means and having a notch which is periodically engaged by said table-pin at a predetermined point in a revolution thereof whereby predetermined movement is imparted to said link and means with respect to said wheel, and means normally maintaining said link and first means in one position of their movement.
19. In a machine of the class described, a rotatable work carrying table having a pin projecting therefrom for revolute movements therewith, an abrading-wheel for acting on a work piece carried by said table at a predetermined point in a revolution thereof, an oscillatory arm movable toward and away from said wheel, an abrading member carried by said arm, a lever connected to said arm for limited rocking movements relative thereto, a link extending from said lever and adapted to be periodically engaged and moved by said table-pin to impart predetermined rocking movements to both said lever and arm, and means operated by relative rocking movements of said lever and arm to adjust said member with respect to said arm.
20. In a machine of the class described, a revolute work carrying arm, means for introducing a work piece in carrying position on said arm, means for acting on the work piece at a predetermined point in its movement with the arm, and a delivery wheel operable to act on said work piece at a predetermined point in its movement with the arm to discharge it from the arm.
- In testimony whereof I have hereunto signed my name to this specification.

FRANK H. MOONEY.
